GRINDING WHEEL DRESSER

Henry W. Kropf, Muskegon Heights, Mich., assignor to Brickner-Kropf Machine Company, Muskegon Heights, Mich., a corporation of Michigan

Application August 15, 1938, Serial No. 224,888

6 Claims. (Cl. 125—11)

This invention relates to grinding wheel dressers, and is concerned with the production of a dresser for grinding wheels whereby the wheel may be dressed to a form having an irregular face. That is, the periphery of the grinding wheel which comes against and contacts the metal to be ground may have an irregular shape given to it transversely of its face to reproduce on a part to be ground such irregular face in relief or the opposite. One example is a grinding wheel with a continuous concave groove around its peripheral face between the sides of the wheel which on the work will produce a corresponding convex rib as illustrated in Fig. 4. It is an object and purpose of my invention to provide a novel and efficient means and one which is simple to construct and reliable in use for dressing wheels of the character stated or many other forms than the concaved groove mentioned as an example. An understanding of the invention and the operation thereof may be had from the following description, taken in connection with the accompanying drawings, in which:

Fig. 1 is a side elevation with a part in section showing the dressing tool of my invention.

Fig. 2 is a vertical section on the plane of the line 2—2 of Fig. 1, looking in the direction indicated by the arrows.

Fig. 3 is a partial plan and horizontal section, the post holding the dressing diamond being shown in section.

Fig. 4 is a plan view of a portion of the wheel which has been dressed in operative position against a part to be ground.

Like reference characters refer to like parts in the different figures of the drawings.

In the construction illustrated in the drawings, a supporting or base plate 1, preferably of cast iron or mild steel, at one end thereof has a transverse bar 2 secured at the upper side of the plate, above and lengthwise of which is a second bar 3 which may be termed a clamping bar and which is clamped against the bar 2 by clamping screws 4, one at each end of the bar 3, as shown. The bar 2 may be secured to the base plate 1 by screws indicated in dotted outline 5 in Fig. 1, passing upwardly through the base plate 1 and threading into the bar at 2. The bar at 2 is preferably of non-magnetic material for a reason which will hereinafter be stated.

The clamping bar 4 is used to clamp a template 8 between it and the bar 2. Such template 8 is a flat plate, at the rear edge of which appears a concaved recess 7. Such recess 7 is for the purpose of showing one example of the form

to which the face of a grinding wheel is to be dressed, but it is to be understood that the rear edge of the template may have many other shapes and is designed as to the shape selected in accordance with the form and configuration that the peripheral grinding face of the grinding wheel is to take. At the upper side of the bar 3 a block 8 with a passage at the underside thereof from front to rear is either integrally formed or is secured to said bar 3 for the purpose of attaching a dust guard 9 which extends upwardly and to the rear at an angle to the vertical, the lower end portion thereof being narrowed in width and turned horizontally as at 10 for entrance into the rectangular passage at the lower side of the part 8 and over the bar 3.

A combined carrier for the dressing or cutting diamond and holder for a feeler to engage the edge of the template is used. It comprises a base 11 from which a vertical post 12 extends upwardly, at the upper end of which is a horizontal sleeve 13, in the front end of which a holder 14 for a diamond cutter 15 may be releasably secured. The head of the holder 14, as shown in the drawings is of conical form but it may take other shapes, as will be later described.

At the upper side and front portion of the base 11 a feeler 16 having a forwardly projecting tapered portion 17, the angular relation of the sides of which are the same as the angular relations of the sides of the head of the holder 14, is clamped upon a raised section 18 having a flat horizontal upper face by means of a clamping screw 19. The screw 19 passes through an opening or slot in the feeler member 16, permitting adjustment of the feeler member which must be located directly below the diamond holder 14 with the pointed end of the tapered section 17 directly below and in the same vertical plane with the point of the diamond cutter 15, and with the angular sides of the part 17 in inclined planes coincident with the planes of the sides of the conical holder 14.

In dressing the grinding wheel 20, the base 1 may be placed upon a magnetic chuck indicated at 21, located properly with respect to the grinding wheel and then magnetically held by the chuck through turning on the electric current. The center of the diamond radius 15 must be in line with the axis of the grinding wheel about which the wheel turns. The base 1 at least, of the diamond and feeler holder and carrier, is of non-magnetic material whereby it may be freely moved over the plate 1 without being affected by the magnetic chuck. The point of the front

portion 17 of the feeler 16 is brought against the rear edge of the template 6 and the post 12 and plate 11 operated by the hands of the operator and with the feeler held against the rear edge of the template 6, may be used to dress the peripheral face of the grinding wheel 20 to produce on the face of the grinding wheel a conformity with the rear edge of the template. Various other forms than the groove indicated 5 at 7 may be used in the rear edge of the template to produce corresponding peripheral patterns around the peripheral grinding face of the grinding wheel. The dust from the grinding wheel is carried downwardly to the dust guard 9, 10 deflecting the same forward. The non-magnetic character of the bar 2 is also to avoid any magnetizing effects upon the template 6 from the magnetic chuck 21 on which the tool may be placed and held. Of course, when the tool is 15 held some other way than magnetically, it makes little difference that the bar 2 or the part 11 should be of non-magnetic material, but in most cases the dressing tool will be used in conjunction with a magnetic chuck.

20 The diamond may have any radii or may have a knife edge. This will not alter the working of the device providing the feeler is shaped to the same outline. With a dressing tool or device made in accordance with my invention, it is possible to grind duplicate contours, previously heretofore considered a substantial mechanical impossibility. The grinding wheel may be very readily dressed to a desired or selected contour by providing a template in accordance therewith. The dust guard protects the template and the feeler from grit or dust cut from the grinding wheel which might come between the two and result in abrasion.

25 The invention is of a very practical and useful nature. It is defined in the appended claims and is to be considered comprehensive of all forms of structure coming within the scope of said claims.

I claim:

40 1. Apparatus for shaping grinding wheels to a desired contour comprising, a base member, a template mounted thereon having a predetermined contour at one edge to be reproduced in the peripheral face of a grinding wheel, a member having a base adapted to be moved horizontally over the upper side of the first mentioned base in any direction, a holder for a wheel dressing implement connected with and located above said second base, a dressing implement carried by said holder, said wheel dressing implement being adapted to be pointed toward and located 45 in the same horizontal plane with the axis about which the grinding wheel to be dressed rotates, and a feeler mounted on said second base adapted to be brought against the contour edge of said template, said feeler having a feeler contact point in direct vertical alignment with the point of said dressing implement, and having sides corresponding to the sides of said dressing implement, as and for the purposes specified.

45 2. Apparatus for shaping the peripheral face of a grinding wheel to a desired contour comprising, a base member having a flat upper side, a template secured at the forward end and above said base member, said template being positioned substantially horizontal and having its rear edge shaped in accordance with a desired contour to be given to a grinding wheel, a member including a base structure having a flat under side adapted to be moved slidably over the upper side

5 of the first base member in any direction, a post extending upwardly from said second base, a horizontally located dressing tool holder carried by said post and extending in a forward direction, a dressing tool carried by said holder, having a head with a dressing point at the front end thereof, a feeler adjustably mounted at the upper side of said second base member having a pointed front end portion, the end of which is in direct vertical alignment with the front end of the 10 dressing tool and having sides corresponding to the sides of said dressing tool, said feeler at its forward end being adapted to follow the contour at the rear edge of said template, as specified.

15 3. Apparatus for shaping grinding wheels to a desired contour comprising, a supporting base having a flat upper side, said base being of magnetic attractive material, a bar secured across one end of the base and above the same, said bar being of non-magnetic material, a feeler plate of sheet metal adjustably clamped at the upper side of the bar and having a rear edge shaped to a preselected contour, a dressing tool and feeler carrying member including a base of non-magnetic attractive material, the underside of which is flat and is adapted to be moved over the upper side of the first named base in any direction that it may be moved, a wheel dressing tool carried on and above said second base, said tool being pointed in a forward direction, a feeler adjustably mounted at the upper side of said second base pointed in the same direction as the dressing tool and having its foremost point in direct vertical alignment with the foremost point of the dressing tool and having its side contours in conformity with the side contours of the dressing tool, said feeler being adapted to be held against the template and moved therewith to follow the contour thereof, as specified.

20 4. Apparatus for shaping grinding wheels to a desired contour comprising, a supporting base member of magnet attractive material adapting the same to be connected with and held upon a magnetic chuck, a template carried by and at the front side of said base, means for mounting said template on the base including a member of non-magnetic material between said base and template, said template at its rear edge having a contour preselected as the contour to which the peripheral surface of the grinding wheel is to be dressed, a dressing tool and feeler carrier located above said base back of the template including a lower base member of non-magnetic material having a horizontal under surface to move freely over the upper surface of the first base member, a dressing tool carried on and above said second base member pointed in a forward direction, said dressing tool including a conical head and a dressing terminal point at the apex thereof, and a feeler adjustably mounted at the upper side and front portion of the second base member comprising a flat horizontal plate having a pointed forward portion with tapered sides, the point of the apex of which is in direct vertical alignment with the point of said terminal dressing point, and the sides of said tapered portion being in planes coincident with the horizontal sides of said conical head, as specified.

25 5. A construction containing the elements in combination defined in claim 4, and a guard located above and extending upwardly and rearwardly over said template and feeler and below

the dressing tool, as and for the purposes specified.

6. Apparatus for shaping grinding wheels to a desired contour comprising, a base member having a flat horizontal upper side, a horizontally disposed template mounted on and above said base at one end thereof having an edge shaped to preselected contour which extends over the base member, a member having a base with a flat under side adapted to rest upon and move over the upper side of the first mentioned base in any direction, a holder for a wheel dressing implement connected with and located above

said second base, a wheel dressing implement secured in said holder adapted to be pointed toward and have its dressing end lie in the same horizontal plane with the axis about which the grinding wheel to be dressed rotates, and a feeler mounted on said second base in substantially the same horizontal plane with said template, said feeler having a free end to bear against the template and follow the contour thereof, the point of engagement of the feeler with the template being in direct vertical alinement with the outermost point of the dressing implement. 5 10
